Austin D. Moss,

J Peaney Kelly attorney

Patented Oct. 2, 1923.

UNITED STATES PATENT OFFICE.

AUSTIN D. MOSS, OF SISTERSVILLE, WEST VIRGINIA.

COMBINATION CHAIR, SWING, AND HAMMOCK.

Application filed September 14, 1920. Serial No. 410,097.

To all whom it may concern:

Be it known that AUSTIN D. Moss, a citizen of the United States, residing at Sistersville, in the State of West Virginia, has invented certain new and useful Improvements in Combination Chairs, Swings, and Hammocks, of which the following is a specification.

The present invention relates to improvements in a combined chair, swing and hammock.

The principal object of the invention is to provide a device as outlined above which shall be comfortable, automatic in operation, durable, require but a minimum space and cheaply manufactured.

Various other objects and advantages of my invention will become apparent during the continuance of the following description.

20 In the drawing:

Figure 1 is a view in side elevation showing my invention as in its preferred embodiment.

Figure 2 is a view in front elevation.

25 Figure 3 is a view in side elevation showing the device with the back tilted back-wardly so as to form a hammock.

In reducing my invention to practice I find it expedient not to limit the device of 30 my invention to any particular form of support or supporting structure. In other words it is to be distinctly understood that the combined chair, swing and hammock may be suspended from the roof of a porch 35 or the like, or from an independent and separate structure such as now used in connection with lawn swings, etc., should occasion so require. Consequently in the present illustration a supporting structure for the device has been eliminated.

40 In the drawing 10 designates depending lugs which either extend from or are connected to the supporting structure for the device (not shown). Links 11 are pivotally connected with the lugs 10 as shown at 45 12 and are in turn pivotally connected to the carrying members 13 and 14 as at 15. The carrying members 13 and 14 are of equal length connected at their lower ends to the spaced side arm members of the chair structure as at 17 and 18, the connection 17 being preferably in the form of short rivets or bolts which pivotally connect the members 13 with the side arms while the connection at 18 includes a transverse rod 19

which extends transversely between the side arms.

The said side arm members are respectively provided with angularly disposed end portions 16 and 20 of different lengths, the shorter end portions 20 being at the rear of the chair structure, downwardly disposed. To the end portions 20 are pivotally connected, as at 21, the members 22 of the back frame which is thus pivotally connected at 65 a point between its upper and lower ends to the lower portions of the shorter ends of the side arm members and at points below the points of connection between the carrying members and the side arm members. 70 Upon reference to Figure 1 it will be observed that while the pivot point or fulcrum of the members 22 is between the ends thereof, it is materially nearer their lower end. The ends 20 of the side arms are further connected by a transverse rod 23 which in addition to forming a connection between the side arms serves to support and limit the tilting movement of the back members 22 as 75 will be observed upon reference to Figure 3. 80

The cross rod 19 further supports foot rest members 24 which are substantially L-shaped when viewed in side elevation and which are connected at their lower ends by means of a foot rest 25. Links 26 movably connect the lower ends of the back members 22 and the foot rest members 24 by such means as shown at 27 and 28.

The seat and back of the device may be formed from a single sheet of heavy canvas 90 as shown at 29 the same being connected at its lower end to the foot rest 25 and at its upper end to a cross rod 30 which connects the upper end of the back members 23. 95

From the above it will be observed that the operator by exerting pressure on the foot rest 25 may propel the swing, or by leaning backwards may cause the same to assume the position shown in Figure 3 so that it may be used as a hammock. It will also be observed that by moving the connections 17 and 18, that is, disconnecting the carrying members 13 and 14 from the side arm 16 the device may be used simply as a chair.

100 105 What is claimed is:

A swing chair comprising spaced side arm members, said members having angularly disposed end portions of different lengths, the shorter end portions being at the rear of the chair structure and downwardly dis- 110

posed, carrying members of equal length pivotally connected together at their upper ends and having their lower ends spaced apart and pivotally connected with the end portions of the longer ends of the side arm members at equal distance below the upper edges thereof, a back frame pivotally connected at a point between its upper and lower ends to the lower portions of the shorter ends of the side arm members and at points below the points of connection between the carrying members and the side arm members, a transverse rod connected with the shorter ends of the side arm members and bridging the space between said members and lying under the intermediate

portion of the back frame, L-shaped foot rest members pivoted to the forward ends of the longer end portions of the side arm members, links pivoted at one end to the lower end of the back frame and pivoted at their other ends to the foot rest members at a point between the ends of the latter, and a strip of fabric material connected at one end with the lower forward ends of the foot rest members and at its other end with the upper rear portion of the back frame and having its intermediate portion attached to the transversely disposed rod.

In testimony whereof I affix my signature.

AUSTIN D. MOSS.
